(57) **CLAIM**

The ornamental design for easy shaker as shown and described.

DESCRIPTION

FIG. 1 is a top perspective view of an easy shaker showing my new design in a collapsed configuration;

FIG. 2 is a bottom perspective view thereof;

FIG. 3 is a front elevational view thereof; with the rear elevation view as a mirror image of the front;

FIG. 4 is a right side elevational view thereof; with the left side elevation view as a mirror image of the right side;

FIG. 5 is a top plan view thereof;

FIG. 6 is a bottom plan view thereof;

FIG. 7 is a sectional exploded view thereof taken along line 7-7 in FIG. 3;

FIG. 8 is a perspective view of the easy shaker in an expanded configuration;

FIG. 9 is a bottom perspective view thereof;

FIG. 10 is a front elevational view thereof; with the rear elevation view as a mirror image of the front;

FIG. 11 is a right side elevational view thereof; with the left side elevation view as a mirror image of the right side;

FIG. 12 is a top plan view thereof;

FIG. 13 is a bottom plan view thereof; and,

FIG. 14 is a top perspective view of the easy shaker in an expanded configuration, with the lid removed.

The broken line in the drawings represent parts of the easy shaker that form no part of the claimed design.

The variations in the surface shading used throughout the drawings, represent a contrast in surface appearance.
